CRIMPER WITH FULL STROKE COMPELLING RATCHET MECHANISM

Henry H. Townshend, Jr., New Haven, Conn., assignor to J. T. Henry Manufacturing Company, Inc., Hamden, Conn., a corporation of Connecticut

Application March 2, 1959, Serial No. 796,531

5 Claims. (Cl. 81—15)

This invention relates to crimpers and relates more particularly to crimpers of the type having means to insure full crimping movement of the crimping dies which are often carried by opposed jaw members arranged in pivotal relation to one another. Crimpers of this type are commonly employed to effect a solderless electrical connection between two conductors, one of which is a wire and the other a ferrule. It will be understood that to effect a satisfactory electrical connection of this type it is necessary to insure that the crimping dies move toward one another to effect a predetermined minimum crimping pressure on the conductors which are constructed to close tolerances. In other words, the crimping dies must be moved toward each other to relative positions which may be termed for lack of a better expression "fully closed" positions.

The present invention contemplates the provision of a crimper actuated by a plunger or piston rod, as opposed to the common manually operated type employing scissor-like handle elements, provided with means for insuring full crimping movement of the crimping dies.

Accordingly, one object of the invention is to provide an improved crimper of the plunger or piston rod operated type having means to insure the movement of the crimping dies necessary to effect a satisfactory crimp.

Another object is to provide a crimper such as characterized above, including a ratchet device having a ratchet element which tends to be maintained in fixed relation to one of the crimping dies.

Still another object of the invention is to provide in such a ratchet device for a crimper a pawl for cooperation with the aforementioned ratchet element and which pawl is movable bodily in a rectilinear course only.

A further object is to provide a mounting for the ratchet element which permits adjustment of the latter in accordance with the desired extent of movement of the crimping die, and which also permits adjustment of the ratchet member to compensate for wear.

In the drawing:

Fig. 1 is a fragmentary plan view, partly broken away, illustrating a crimper embodying the invention;

Fig. 2 is a sectional view taken on line 2—2 of Fig. 1;

Fig. 3 is a sectional view taken on line 3—3 of Fig. 2;

Fig. 4 is a view further illustrating certain parts of the crimper, looking in the direction of the arrows 4—4 in Fig. 1;

Fig. 5 is a fragmentary view generally similar to Fig. 1, illustrating the pawl of the ratchet device in a different position from that shown in Fig. 1; and

Fig. 6 is a view similar to Fig. 5 but illustrating the pawl in still another position.

In the drawing, the jaws of the crimper are indicated generally at 10 and 11. The jaws are provided with a pair of crimping dies 12 arranged in opposing relation to one another and adapted to seat on one another when the jaws are closed. The crimping dies may be removably mounted on the respective jaws in any conventional manner, and the arrangement may be such that

2

dies of different sizes may be mounted on the jaws. The crimper includes a pair of jaw-operating toggle levers 13. In the illustrated form the jaws are mounted on generally triangular shaped plates 14 at opposite sides of the crimper. A pair of bolts 15 extend through the plates 14 and the respective jaws to pivot the jaws for movement between the plates. As best shown in Fig. 2, the plates 14 receive a bolt 16 which extends through a generally tubular support member 17 to support the plates 14. A pin 18 also extends through the plates 14 and the support member 17 at a distance from the bolt 16 to prevent angular movement of the plates on the support member. As shown in the last-mentioned view, the bolt 16 and the pin 18 extend through a somewhat flattened end portion 19 of the tubular member.

Each jaw has a shank provided with a thickened end portion 20 for added strength, and each thickened end portion is slotted, as at 21. The slotted end portion of each shank receives one end of one of the jaw-operating links 13, which end is pivoted thereto by a bolt extending through the shank and the link 13. The jaw-operating links 13, which extend through diametrically opposite slots 23 in the tubular member 17, have their other ends pivotally interconnected, as by a pin 24. The pin 24 connects the links 13 to the outer end portion of an actuating rod, indicated generally at 25, slideable within the tubular support member 17. The actuating rod 25 may be a plunger or a piston rod having movement imparted thereto by a fluid-operated piston, not shown. The actuating rod may have an inner part 27 having a threaded socket 28 receiving the threaded portion of an outer part 29 provided with bifurcations 30 extending to the extreme outer end of the actuating rod. The links 13 extend between the bifurcations, and the pivot 24 for the links 13 is mounted in the bifurcations a distance inwardly from their outer or distal ends, as shown in Fig. 2.

From the foregoing, it will be manifest that when the actuating rod 25 is moved toward the outer end of the tubular support member 17 from the position shown in Fig. 1, the shanks of the jaws are separated through the action of the links 13 to move the dies 12, carried by the jaws, toward one another. The fully closed position of the dies is shown in Fig. 3. Movement of the dies toward one another is not limited by engagement of the jaws with one another but by the seating of one die on the other, as indicated above. It will be understood that the dies are opened by reverse movement of the actuating rod in the support member 17, this movement of the rod serving to draw the shank portions of the jaws toward one another through the links 13.

The ratchet device of the crimper includes a pawl 31 pivoted between the outer or distal ends of the bifurcations of the rod 25, the pawl being pivoted on a pin 32 extending between the bifurcations a distance outwardly from the pivot pin 24 interconnecting the links 13. A thrust member 33, generally similar in outline to the pawl 31, is also supported on the pin 32 and faces in a direction which is generally opposite that in which the pawl faces, as shown in Fig. 1. To prevent the thrust member from moving angularly on the pin 32, another pin 34 extends through the member 33 a distance from the pin 32, the pin 34 being fixedly supported in the bifurcations 30, as shown in Fig. 4. As shown in the last-mentioned view, the portions of the pawl 31 and thrust member 33 through which the pin 32 extends are of reduced thickness and overlapped with one another. A spring 35 is provided to urge the pawl 31 toward the central position thereof shown in Fig. 1. In this position the pawl extends in a plane normal to the plane of the actuating rod 25. As shown in Fig. 4, the spring 35 has a terminal portion 36 snugly received in a small hole in the pawl.

The other terminal of the spring is suitably connected to a pin 37 extending between the bifurcations 39 intermediate the pin 24 and the pin 32, as shown in Fig. 3. The spring has a spiral portion normally embracing the pin 37 somewhat loosely.

The pawl 31 of the ratchet device cooperates with a toothed ratchet element 38 extending along a portion of the edge of the jaw 10 which opposes the jaw 11. The corresponding edge portion 39 of the jaw 11 is somewhat similar in outline to the ratchet element, as shown in Fig. 3. However, the edge portion 39 is smooth instead of toothed and cooperates with the thrust member 33 which is adapted to slide over the smooth surface. As shown in the last-mentioned view, the general outline of the edge portion 39, like the general outline of the ratchet element 38, is somewhat rounded, and, as further shown in this view, the element 38 and the edge portion 39 are disposed intermediate the corresponding crimping dies and the corresponding shank ends of the jaws.

In the illustrated form, the ratchet element 38 is not formed as an integral part of the jaw 10, but is constructed as a part which is mounted on and adjustable with respect to the jaw 10. The ratchet element 38, which is of elongate form, extends generally longitudinally of the jaw 10, and is received in a recess 38a provided in an edge portion of the jaw, the element having a heel portion pivoted in the recess, as at 40. The heel portion of the ratchet element 38 provides an abutment for engagement with the bottom of the recess 39 to limit tilting movement of the toe of the element 38, and in actual practice the ratchet element, which is adjustably mounted on the pivot 40, may have only a very limited range of movement. To tip or swing the toe of the ratchet element outwardly, that is, away from the jaw 10, an adjusting screw 41 is provided in the jaw 10 for engagement with the toe of the element 38. To lock the screw 41 in adjusted position, a set screw 42 is provided in the jaw 10. When the pawl 31 is engaged with the ratchet element 38 during operation of the crimper, the pawl tends to maintain the ratchet element in engagement with the adjusting screw 41. As indicated above, the engagement of the heel portion of the element 38 with the bottom of the recess 38a limits any dislocation of the element 38 with respect to the jaw 10 when the pawl 31 is not engaged with the ratchet element. To permit the pawl 31 to clear the jaw 10 at the toe and heel ends of the ratchet element 38 the jaw is provided with clearances 43 and 44, respectively, in edge portions thereof. The jaw 11 may have its corresponding edge portions shaped in a similar manner.

The operation of the crimper will be manifest from the foregoing description of its construction. When it is desired to crimp together two articles, such as electrical conductors, the articles are placed between the jaws of the crimper while the jaws are in their open positions shown in Fig. 1. When the jaws are in these positions the actuating rod 25 is in a retracted position in the tubular support 17 and the pawl 31 of the ratchet device is located in the clearance 44 of the jaw 10. As shown in the last-mentioned view, portions of the jaws may extend through the respective slots 23 in the tubular member 17 when the jaws are fully opened and, as also shown in this view, the ratchet element 38 may closely approach the edge portion 39 of the jaw 11 when the jaws are fully opened. To close the jaws on articles to be crimped, the actuating rod 25 is extended or moved outwardly in the tubular support member 17 from its retracted position shown in Fig. 1, the rod being moved by fluid or other suitable means. As the rod 25 is extended the links 13, interconnecting the respective jaws with the rod, force the shank portions of the jaws apart.

As this occurs the distal end portion of the operating rod is extended into the widening gap between the ratchet element 38 and the edge portion 39 of the jaw 11. At this time the pawl 31 engages the toothed portion of the

element 38 and is deflected inwardly thereby, that is, in a direction generally opposite the direction of movement of the actuating rod. This deflection of the pawl is shown in Fig. 5. When and as the pawl is engaged in this manner, the thrust member 33 engages and bears

against the edge portion 39 of the jaw 11. The thrust member tends to equalize any bending strain imparted to the actuating rod through engagement of the pawl with the ratchet element 38. The ratchet device is so constructed and arranged that the pawl does not leave the ratchet element 38, but continues to be deflected thereby until the crimping dies are fully seated on one another by full closing movement of the jaws. When the jaws of the crimper are only partially closed, as shown in Fig. 5, the actuating rod may not be retracted due to the angularity of the pawl and its engagement with the ratchet element. This prevents the dies from opening after only partial crimping movement of the dies and insures a satisfactory crimp by making it necessary to extend the rod fully to effect full seating of the crimping dies before the actuating rod may be retracted. The fully extended position of the rod is shown in Fig. 3 and, as shown in this view, the pawl is beyond the ratchet element 38 and disposed in the clearance 43. It will be understood that when the pawl enters the clearance 43 the pawl is centered through the action of the spring 35. The actuating rod may then be retracted to effect opening of the jaws for removal of the crimped articles and as the rod is retracted in tubular support 17 the pawl 31 is once again engaged with the ratchet element 38 and the thrust member 33 engaged with the edge portion 39 of the jaw 11. Here again, the pawl is deflected by the ratchet element in a direction which is generally opposite the direction of movement of the actuating rod, as shown in Fig. 6. When the jaws are fully open the pawl is disengaged from the ratchet and disposed in the clearance 44 of the jaw 10. It will be further understood that, when necessary, the ratchet element may be angularly adjusted in accordance with the size of the crimping dies used in the crimper. Adjustment of the ratchet element may also be desired to compensate for wear. To effect adjustment of the ratchet element it is necessary to first loosen the set screw 42 before turning the adjusting screw 41.

From the foregoing disclosure, it will be manifest that there is provided an improved crimper of the type operated by a plunger or piston which has only a rectilinear movement. The improved crimper has a ratchet device for insuring full crimping movement of the crimping dies, which ratchet device includes a ratchet element which, in operation, tends to be maintained in fixed relation to one of the crimping jaws and the die carried thereby, the ratchet element being adjustable. It will also be understood that the ratchet device of the crimper includes a pawl for cooperation with the ratchet element and which pawl is movable bodily in a rectilinear course only. The crimper of the invention is particularly well suited to crimping together articles, such as electrical conductors, and the crimper is very satisfactory and reliable in operation. Furthermore, it is constructed of few and simple parts and will not readily get out of order.

While only one form of the crimper has been illustrated in the drawing and described above, it will be apparent to those versed in the art that the crimper is susceptible of various modifications and changes in details without departing from the principles of the invention and the scope of the appended claims.

What I claim is:

1. In a crimper, a pair of pivotally interconnected jaws carrying opposed crimping dies swingable with the jaws toward and away from one another, an actuating rod for the crimper jaws, said rod having a rectilinear movement only, jaw-operating means pivotally interconnecting the jaws and the rod for effecting closing movement of the jaws on axial movement of the rod in one direction, and

means to prevent opening of the jaws until after the jaws have reached the fully closed crimping position, the last-named means comprising a ratchet device including a ratchet element carried by the rod and a ratchet element cooperating with the first-mentioned ratchet element and carried by one of the jaws.

2. A crimper as defined in claim 1, wherein one of the ratchet elements is a pivotally mounted pawl and the other ratchet element is a toothed part which during a crimping operation tends to be maintained in fixed relation to the part which carries it.

3. In a crimper, a pair of pivotally interconnected jaws carrying opposed crimping dies swingable with the jaws toward and away from one another, an actuating rod for the crimper jaws, said rod having a rectilinear movement only, jaw-operating means pivotally interconnecting the jaws and the rod for effecting closing movement of the jaws on axial movement of the rod in one direction, and means to prevent opening of the jaws until after the jaws have reached the fully closed crimping position, the last-named means comprising a ratchet device including a pivotally mounted pawl carried by the rod and a toothed part carried by one of the jaws for cooperation with the pawl.

4. In a crimper, a pair of jaws carrying opposed crimping dies, an elongated tubular support member, means pivoting the jaws on one end of said member for swinging movement toward and away from one another, an actuating rod slidable in said member in one direction

5 10 15 20 25 for swinging the jaws toward each other and slidable in the other direction for swinging the jaws apart, jaw-operating links pivotally interconnecting the jaws and the actuating rod, the links being pivoted in the end portion of the rod nearest said end of said member and extending through the wall structure of the tubular member, a pawl pivoted in said end portion of the rod and extending through said wall structure, and a toothed ratchet element for cooperation with said pawl to prevent opening of the jaws until after the jaws have reached fully closed crimping positions, said ratchet element being carried by one of the jaws and tending to be maintained in fixed relation thereto during a crimping operation.

5. A crimper as defined in claim 3, where the jaw which carries the toothed part is provided with means mounting the toothed part for angular adjustment of said part relatively to the last-mentioned jaw and the pawl to vary the throw of the jaws.
